UNITED STATES PATENT OFFICE.

WILLIAM M. WATTIE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

HARNESS MOTION FOR LOOMS.

Application filed November 25, 1927. Serial No. 235,575.

This invention relates to improvements in harness motions for looms and it is the general object of the invention to provide mechanism whereby the period of operation of the harness frames may be varied so that the cycle of movement of the harness motion may be accomplished in a given number of picks of the loom under certain circumstances and completed in a different number 10 of picks of the loom under other circumstances.

In co-pending application Ser. No. 235,662 filed by Howard there is set forth a mechanism which permits a shift in the control 15 for the harness frames so that when one part of the fabric is being woven the harness frames will complete their cycle of movement in a given number of picks and when another part of the fabric is being woven 20 the cycle of movement of the harness frames will be completed in a different number of picks. Such a mechanism is desirable in weaving certain kinds of Terry towels. It is common to have the body of a Terry 25 towel woven with a so-called three pick Terry, that is, so constructed that for every third pick of filling there will be a row of pile loops. When weaving the border, however, a different weave is employed which 30 may require the harnesses to be held up for two picks and then down for two picks. It is an important object of my present invention to provide mechanism to give the harness frames the various movements as specified with a fewer number of parts than those 35 employed in the aforesaid application to Howard.

It is a more specific object of my invention to provide a treadle lever operatively 40 connected at all times to the harness frames which control the ground warps and to provide two actuating elements such as rotating cams which complete their movements in a different number of picks, the treadle lever 45 being provided with a device which connects the same with one or the other of said actuating elements depending upon the character of fabric being woven.

With these and other objects in view 50 which will appear as the description proceeds, my invention resides in the combination and arrangement of parts hereinafter described and set forth in the claims.

In the accompanying drawings wherein one form of my invention is shown, 55

Fig. 1 is a rear elevation of a loom provided with my invention, certain parts being removed for the sake of clearness,

Fig. 2 is an end elevation taken in the direction of arrow 2, Fig. 1 with certain parts removed, 60

Fig. 3 is an enlarged vertical section on line 3—3 of Fig. 1,

Fig. 4 is a horizontal section on line 4—4 of Fig. 3, 65

Fig. 5 is a vertical section on line 5—5 of Fig. 3,

Figs. 6 and 7 are details showing the three and four pick cams, respectively, and

Fig. 8 is a view similar to a portion of Fig. 5 but showing the parts in a different position. 70

Referring particularly to Figs. 1 and 2 the loom 10 is provided with ground and pile warp beams 11 and 12, respectively, the 75 ground warp G of the beam 11 passing over a whip roll 13 and being divided between rear and front harness frames 14 and 15, respectively. The Terry warp T from the beam 12 extends forwardly and may be controlled by a jacquard pattern mechanism indicated diagrammatically at J, Fig. 1, to form any figures which may be desired in the fabric. The frames 14 and 15 are connected together by straps 16 which extend 80 over rollers 17 carried by an oscillatable shaft 18 supported by fixed bearings 19 rigid with the loom frame.

The loom is provided with a bottom shaft 20 which makes a revolution every second 90 pick of the loom to actuate a picking motion not shown. The Terry forming mechanism has been omitted but may be substantially the same as shown in patent to Bardsley No. 937,139 and the controls for the Terry warps 95 T have been omitted from Fig. 2 as they are well understood. The matter thus far described is of common construction in Terry towel looms and forms no part of my present invention.

In carrying my improvements into effect I provide a frame 30 which as indicated in Fig. 3 may be bolted to the rear and front cross girts 31 and 32, respectively, of the loom frame. Stub shaft 33 is held in said 105 frame by set screw 34 and has freely rotat-

able thereon cams 35 and 36 shown in Figs. 6 and 7, respectively. The cam 35 has a low part 37 and a high portion 38 so proportioned as to be operative throughout approximately $\frac{1}{3}$ of a revolution of the cam. Cam 36 has a low portion 39 and a high portion 40, said portions being approximately equal as regard angular displacement, the low portion 39 being effective for approximately two picks and the high portion 40 for two picks also as will be described herein-after.

The cam 35 has a hub 41 to which is keyed a gear 42 which as shown herein meshes with the intermediate step 43 of a cone gear 44. The other steps 45 and 46 are positioned to cooperate with different sized gears which may be secured to the hub 41 but the arrangement as set forth herein is such that the cam 35 will be given a rotation every third pick of the loom while the bottom shaft 20 receives a complete revolution every second pick.

The cam 36 has a hub 47 to which is keyed a gear 48 meshing with a pinion 49 keyed to the bottom shaft 20 and the ratio of the gear 48 and pinion 49 is such that the cam 36 will be given a revolution every fourth pick of the loom. As the loom continues to run the cams rotate constantly but in cycles of different numbers of picks.

A fixed bracket 50 supports a pin 51 on which is mounted hub 52 of the treadle lever 53, the lower end of which is provided with notches 54. A link 55 located in one of the notches 54 is attached to the lower end of a rod 56 the upper end of which is connected as at 57 to the harness frame 15. The other harness frame 14 is connected by means of a spring 58 to a guide bracket 59 which is forked as at 60 in Fig. 5 to receive and guide the treadle lever. A stop screw 61 is adjustably held in the treadle lever by means of lock nut 62 and is positioned to engage the underside of cross girts 31 to limit upward movement of the treadle.

The mechanism for imparting movement of the cams to the treadle lever includes a rocking lever 63 secured to rock shaft 64 extending through arms 65 preferably cast integral with the treadle lever. Said rock shaft has a collar 66 secured thereto which receives one end of a torsion spring 67 the other end of which enters a lug 68 integral with the treadle lever. Said shaft extends through the lug 68 and has secured thereto an arm 69 the lower end of which is attached to rod 70 extending to the right as shown at the bottom of Fig. 1. The rocking lever 63 is provided with a pivoted shoe 71 which is mounted for limited pivoted movement around a pin 72 passing between and secured to the ears 73 of the rocking lever 63. Said shoe is provided with face 74 which is preferably broader than the dis-

tance between the surfaces 38 and 40 of the cams 35 and 36, respectively, and as shown in Fig. 5 the lower side of said shoe may be beveled as at 75 to engage the surface 76 on the rock lever 63 between the ears 73. The purpose of this construction is to limit the movement of the shoe but permit the same to assume two operative angular positions with respect to the lever 63.

As shown more particularly in Fig. 1 the rod 70 is connected to an angle lever 77 attached to another rod 78. This latter rod is connected to a second lever 79 connected to a horizontal rod 80 which extends to and has operative connection with the indicator mechanism I. Said mechanism I is substantially the same as that shown in Patent No. 1,626,723 and forms no part of my present invention, the same being what is generally termed a jacquard indicator and being attached to the jacquard jacks 91 and 92. The indicator mechanism and the jacquard determine the position of lever 63 and therefore the motion of the treadle lever.

In operation with the parts in the position shown in full lines in Figs. 5 and 8 the cam 35 will engage the shoe 71 to depress the same once every third pick of the loom when the gearing is that shown in Fig. 5. As the cam face 38 depresses the shoe the treadle lever will be moved downwardly to cause a corresponding downward movement of the harness frame 15 and a rising movement of the frame 14. As the cam 35 continues to turn the treadle will move upwardly and the shoe will be moved to the full line position shown in Fig. 8 relatively to the stub shaft 33 and will assume this position which they assume when weaving the Terry or body part of the fabric.

When it is desired to pass from the body to the border jack 92 will be lifted and as set forth in the aforesaid Patent No. 1,626,723 the indicator mechanism will operate to cause a right hand movement of the rod 70 which will move the lever 63 from the full to the dotted line position shown in Fig. 8. This shift in the position of the rocking lever 63 takes place when the low parts of both cams are adjacent but spaced from the shoe by screw 61 being in engagement with the left girt 31. In this way the shoe is free to move without obstruction on the part of the driving cams. When in the dotted line position shown in Fig. 8 the shoe will be depressed by the cam 36 so that as the loom continues to run the treadle lever will be held down for two picks and will then be up for two picks, the low part 39 of the cam 36 permitting the spring 58 to lift the treadle lever and harness frame 15 while depressing the harness frame 14. When it is again desired to weave Terry the jack 91 will be raised to cause the left hand movement of rod 70, the spring 67 at this time assist-

ing in returning the shoe 71 to the full line position shown in Figs. 5 and 8. By reason of the mechanism described and the control exercised by the jacquard and the indicator mechanism it is possible to place the shoe 71 in the path of one or the other of the constantly moving actuating cams 35 or 36 and the harness frames will be given movements of different characters depending upon which cam is operatively related thereto.

When the rocking lever 63 is in the full line position shown in Figs. 5 and 8 a toe 80 thereon will engage the treadle lever to limit angular movement of said lever 63 to cause depression of the treadle lever. When the lever 63 is rocked to the position shown in dotted lines in Fig. 8 it will engage the adjustable screw 81 carried by the treadle lever to cause downward motion of the treadle lever.

From the foregoing it will be seen that I have provided a harness motion having a pair of constantly moving actuator cams, the cams having complete movements in a different number of picks and that the treadle lever which controls the harness frames may be operatively related to either of said cams by a control exercised by the jacquard or other pattern mechanism. It will further be seen that the rounded portion 75 of the shoe cooperates with the surface 76 to place the shoe in its operative positions relatively to the rocking lever 63.

Having thus described my invention it will be seen that changes and modifications may be made therein by those skilled in the art without departing from the spirit and scope of the invention and I do not wish to be limited to the details herein disclosed, but what I claim is:

1. In a harness motion for a loom having a pair of oppositely moving harness frames to be moved by a treadle lever, an actuator cam having a motion the cycle of which is completed in a given number of picks of the loom, a second actuator cam for a motion the cycle of which is completed in a different number of picks of the loom, and a device moving with but movably mounted with respect to the treadle lever to have direct engagement with either cam whereby either cam causes movement of the treadle lever.

2. In a harness motion for a loom having a pair of oppositely moving harness frames to be moved by a treadle lever, an actuator cam having a motion the cycle of which is completed in a given number of picks of

the loom, a second actuator cam for a motion the cycle of which is completed in a different number of picks of the loom, a rocking lever pivotally mounted on the treadle lever and moving with the latter and causing movement of the latter when moved, and means to move said lever to have direct operative relation with either of said actuating cams.

3. In a harness motion for a loom having a pair of oppositely moving harness frames to be moved by a treadle lever, an actuator cam having a motion the cycle of which is completed in a given number of picks of the loom, a second actuator cam for a motion the cycle of which is completed in a different number of picks of the loom, pattern mechanism, a rocking lever pivotally mounted on the treadle lever, said pattern mechanism being effective to move the rocking lever to cause the same to have direct engagement with either actuating cam.

4. In a harness motion for a loom having a pair of oppositely moving harness frames to be moved by a treadle lever, an actuator cam having a motion the cycle of which is completed in a given number of picks of the loom, a second actuator cam for a motion the cycle of which is completed in a different number of picks of the loom, a rocking lever mounted on the treadle lever, a shoe pivoted to the rocking lever and positioned for engagement with either cam, and pattern mechanism to move said rocking lever and shoe to cause the latter to be operatively placed for direct engagement with either actuating cam.

5. In a harness motion for a loom having a pair of oppositely moving harness frames to be moved by a treadle lever, an actuator cam having a motion the cycle of which is completed in a given number of picks of the loom, a second actuator cam for a motion the cycle of which is completed in a different number of picks of the loom, a rocking lever pivotally mounted on the treadle lever and capable of assuming two angular positions relatively to said treadle lever, and cooperating stop means carried by the treadle and rocking levers to hold said rocking lever in either of its angular positions relatively to the treadle lever for direct engagement with one or the other of the cams.

In testimony whereof I have hereunto affixed my signature.

WILLIAM M. WATTIE.
